PUSHBUTTON SWITCH OR SIMILAR ARTICLE

Lee O. Woods, Morrison, Ill., assignor to General Electric Company, a corporation of New York

Filed Apr. 2, 1963, Ser. No. 74,262

Term of patent 14 years

(Cl. D26—13)

Fig.1.

Fig.2.

Fig.3.

Fig.4

FIG. 1 is a left side, top and front perspective view of a pushbutton switch or similar article, showing my new design;

FIG. 2 is a front elevational view;

FIG. 3 is a bottom plan view, the top being substantially a mirror image thereof; and

FIG. 4 is a side elevational view, the opposite side being substantially a mirror image thereof.

The crosshatching shown in the linear row of elements that extend from the front face of the switch or similar article in FIGS. 1 and 2 provides a contrast in appearance.

The back of the pushbutton switch or similar article is substantially flat and unornamented.

I claim:

The ornamental design for a pushbutton switch or similar article, substantially as shown and described.
